TO THE UNION SWITCH AND SIGNAL COMPANY, OF SWISSVALE,
PENNSYLVANIA, A CORPORATION OF PENNSYLVANIA.

RAILWAY SIGNALING SYSTEM.

No. 825,988.

Specification of Letters Patent.

Patented July 17, 1906.

Application filed June 20, 1905. Serial No. 268,151.

To all whom it may concern:

Be it known that I, LOUIS H. THULLEN, a citizen of the United States, residing at Edgewood Park, in the county of Allegheny 5 and State of Pennsylvania, have invented certain new and useful Improvements in Railway Signaling Systems, of which the following is a specification.

My invention relates to railway signaling systems in which track-circuits are used for the control of signals, and particularly to those cases where a direct current is used in the said track-circuits.

In the accompanying drawings, Figure 1 and Fig. 2, I have diagrammatically illustrated a portion of a railway comprising one complete track-circuit with the signal controlled thereby and portions of two adjacent track-circuits. I have also shown in diagrammatic form the relays controlling the signals and the apparatus embodying my invention.

I will now describe the said apparatus and then point out the novel features thereof 25 in claims.

Referring to Fig. 1, A designates a portion of a railway having one rail divided to form sections D D' D², &c., by insulation a a', &c. Each of these sections is called a "block-section" 30 and comprises a track-circuit which includes a source of current-supply B B', &c., at one end of the block-section, a relay device R R', &c., at the other end of the section adapted to respond in the movements of its armature to the presence or absence in its 35 coil of current furnished by the said source of supply, and the rails of the block-section which are used as conductors of the current from the source of supply to the relay. A 40 signal S S', &c., is located at the entrance end of each block-section for the purpose of controlling the movements of trains over said section, and the movements of each signal to the "danger" or "safety" position of 45 indication are controlled by the presence or absence of trains or cars in the block-sections to which they respectively govern the entrance.

B B' designate, respectively, the sources 50 of current-supply for the track-circuits D and D', that for D² not being shown in the

drawings. In this particular case I have shown the sources of current-supply B and B' as being secondary or "storage" cells, which are charged in a manner well known to the art from a source of direct current G, located at any convenient point along the railway, the charging-current from the said source G being conveyed to the several cells or batteries of cells B B', &c., along suitable 60 main conductors C and C'. The "cells" B B', &c., as I shall hereinafter term them, are furnished in duplicate for each track-section, and appropriate switching arrangements H H' are provided in each case for 65 changing over the cell connections to the charging-mains C C' and to the track-rails of their respective block-sections, so that one cell of any given pair may be discharging onto the track-circuit while the other cell 70 of the same pair is being charged from the source G.

E designates a source of alternating-current supply, one terminal of which is connected to main conductor C of the battery- 75 charging system and the other terminal to the continuous rail L of the railway.

T T' are transformers, one being provided for each track-circuit. The primary coil p p', &c., of each transformer has one terminal 80 connected to the main conductor C, and the other terminal is connected, through the condenser K' K², to the continuous rail L. The secondary coil s s', &c., of each transformer may be connected up in various different 85 ways; of which I have shown two in Fig. 1 and two more in Fig. 2. In Fig. 1 the secondary coil s of transformer T has one terminal t connected to the sectional rail r' and the other terminal t' to the continuous rail 90 L. In other words, it is connected in multiple circuit with the relay R. The secondary coil s' of the transformer T' has one terminal t² connected to the relay R' and the other terminal t³ to one of the track-rails, the remaining terminal of the said relay being connected to the other track-rail at the point l, so that the said secondary coil s' is in series with the coils of the relay R'. The points F and J on the main conductor C, where the 100 primary coils of transformers T and T' are respectively connected to the said main C,

are necessarily situated at some distance from each other. This distance may be a mile or more or less. In any case it will be sufficient to cause a certain drop of potential between the points J and F in the direct current derived from source G. Supposing the two transformers T and T' to have the same resistance in their primary coils p and p' , it follows that a like difference of potential will exist between the points j and f where the said primary coils p' and p are respectively connected to the continuous rail L, and this difference of potential between j and f tends to cause a flow of direct current other than the return propulsion-current from the source G along the rail between these points. Such a flow of direct current from such a source would be likely to derange the operation of the track-relays R R', which are responsive to the movement of their armatures to the presence of direct current flowing in the rails to which they are connected. In order to prevent any derangement of the signal system arising from this cause, I provide means for preventing the flow of direct current through the primary circuits of the transformers T T' by inserting condensers K' K² in the said circuits. The said condensers are constructed according to rules well known in the art and are adapted to act as insulators of the direct current, though they will transmit the alternating current of the circuits of which they form parts. The secondary coil s of the transformer T, as I have already explained, is connected in multiple circuit with the relay R across the track-rails, and I therefore insert a condenser K in the circuit of said secondary coil s in order to prevent the direct current of the track-circuit—that is, the current from source B'—from traversing the said secondary coil s , and thereby short-circuiting the relay R.

In Fig. 2 the secondary coils s^2 s^3 of the transformers T² T³ are not connected to the track-rails as in Fig. 1. The wire connecting the terminals of the secondary coil s^2 of transformer T² is looped in one or more convolutions around the magnet-core m of relay R², and the wire connecting the terminals of the secondary coil s^3 of transformer T³ is looped in one or more convolutions around the armature n of relay R³.

As in Fig. 1, A designates in Fig. 2 a portion of a railway having one rail divided to form sections D³ D⁴ D⁵, &c., by insulation a² a³, &c. B³ B⁴ designate the sources of current-supply for the sections D³ D⁴, respectively, the said sources in this case being shown as primary batteries, which may be of any suitable type. As regards the operation of my invention, it is a matter of indifference as to whether a primary or secondary battery or any other source of direct current is used for supplying current to the track-circuits.

In Fig. 1 I have shown how one of the battery-charging wires of a storage-battery system may be used as a conductor for the alternating current which I use in the apparatus embodying my invention. In Fig. 2, where primary batteries are used as sources of current-supply for the track-circuits, no charging-wires are employed, there being no storage batteries to charge. In this case I accordingly employ a wire or other suitable conductor C² in the place of the conductor C of Fig. 1, and I connect one terminal of the source of alternating-current supply E to the said conductor C² and the other terminal of E to the continuous track-rail L, as in Fig. 1. S² and S³ designate signals controlling the entrance of trains to the block-sections D⁴ and D⁵, respectively. T² designates a transformer having one terminal of its primary coil p^2 connected to the conductor C² at the point F and the other terminal connected to the continuous rail L at the point f. R² designates a relay having its terminals connected, respectively, to the two track-rails of the track-section D⁴ at one end of the said section and adapted to respond in the movement of its armature to the presence or absence of direct current in its coils, the said direct current being derived from the source B⁴ and being conveyed in the usual well-known manner through the track-rails from the said source B⁴ to the said relay R². In like manner, R³ designates a relay having its terminals connected to the track-rails of the section D⁵ and deriving its operating-current from a source of direct-current supply which is located at the other end of the section D⁵, but is not shown in the drawings. T³ designates a transformer having one terminal of its primary coil p^3 connected to the conductor C² at the point J and the other terminal to the continuous rail L at j.

From the foregoing description it will be seen that I have shown in Fig. 1 two different means whereby I induce an alternating current to flow through the winding of a track-relay concurrently with the flow of direct current through the same winding, the said direct current being derived from the ordinary source of current-supply. In the case of relay R² in Fig. 2 I employ a separate winding on the relay-core and provide means for causing an alternating current to flow through the said separate winding, and in the case of relay R³, Fig. 2, I cause an alternating current to flow through a winding which embraces or encircles the armature of said relay. In each of the above-cited cases the magnetic lines of force generated by the alternating current will cut through or embrace the whole or a part of the magnetic field generated by the direct current which flows through the winding of the relays. The flow of magnetic lines of force caused by the alternating current in

the magnetic field of the relay will of course change its direction of flow twice in each cycle of the alternating current and will consequently tend to neutralize the magnetic effects of the direct current, and upon the cessation of the flow of direct current through the relay-windings any residual magnetism which might otherwise remain in the relay coil or armature will thereby be neutralized. 5 and the sensitiveness of the relay thereby greatly enhanced. The amount or strength of the alternating current which I thus introduce into the magnetic field of the relay for the purpose of destroying or neutralizing the residual magnetism may be very small indeed—so small, in fact, that it will not affect the ordinary operation of the relay in its energized state. Various other means besides those which I have shown may be employed 10 for inducing an alternating current to flow in the magnetic field of a relay.

What I claim as my invention is—

1. In a railway signaling system having a plurality of block-sections, the combination 25 with a track-circuit for each block-section, comprising a relay, of means comprising a source of alternating current for reducing the magnetic field of the relay when a train enters a block-section.

2. In a railway signaling system having one or more block-sections, the combination of one or more track-circuits for each block-section, each track-circuit comprising a source of current-supply and a relay device 35 adapted to respond in the movement of its armature to the presence or absence in its coils of current derived from the said source of supply, and means for causing alternating current to traverse the magnetic field of said 40 relay.

3. In a railway signaling system having one or more block-sections, the combination of one or more track-circuits for each block-section, each track-circuit comprising a source of direct-current supply and a relay device adapted to respond in the movement of its armature to the presence or absence of current in its coils derived from said source, a source of alternating-current supply and 45 means for causing current derived from said source of alternating current to traverse the magnetic field of said relay.

4. In a railway signaling system having one or more block-sections, the combination 55 of one or more track-circuits for each block-section, each track-circuit comprising one or more secondary batteries and a relay device adapted to respond in the movement of its armature to the presence or absence of current derived from said secondary batteries in its coils, a source of direct-current supply for charging the said secondary batteries, wires or conductors for conveying the charging-current from the said source to the place or 60 places where said current is to be used, means for connecting each of said secondary batteries alternately with the said conductors and with the track-rails of the block-section, a source of alternating-current supply and means for utilizing one of the conductors of the battery-charging system as one conductor of the alternating current and means for using one or both track-rails of the railway as the other conductor of the said alternating current, and means for causing alternating current derived from said source to traverse the 65

where said current is to be used, means for connecting each of said secondary batteries alternately with the said conductors and with the track-rails of the block-section, a source of alternating-current supply and means for utilizing one of the conductors of the battery-charging system as one conductor of the alternating current and means for using one or both track-rails of the railway as the other conductor of the said alternating current, and means for causing alternating current 70 derived from said source to traverse the direct-current winding of the relay device.

5. In a railway signaling system having one or more block-sections, the combination of one or more track-circuits for each block-section, each track-circuit comprising one or more secondary batteries and a relay device adapted to respond in the movement of its armature to the presence or absence of current derived from said secondary batteries in 80 its coils, a source of direct-current supply for charging the said secondary batteries, wires or conductors for conveying the charging-current from the said source to the place or places where said current is to be used, means for connecting each of said secondary batteries alternately with the said conductors and with the track-rails of the block-section, a source of alternating-current supply and means for utilizing one of the conductors of the battery-charging system as one conductor of the alternating current and means for using one or both track-rails of the railway as the other conductor of the said alternating current, and means for causing alternating current 85 derived from said source to traverse the winding on the core of the relay device.

6. In a railway signaling system having one or more block-sections, the combination of one or more track-circuits for each block-section, each track-circuit comprising one or more secondary batteries and a relay device adapted to respond in the movement of its armature to the presence or absence of current derived from said secondary batteries in 105 its coils, a source of direct-current supply for charging the said secondary batteries, wires or conductors for conveying the charging-current from the said source to the place or places where said current is to be used, means for connecting each of said secondary batteries 110 alternately with the said conductors and with the track-rails of the block-section, a source of alternating-current supply and means for utilizing one of the conductors of the battery-charging system as one conductor of the alternating current and means for using one or both track-rails of the railway as the other conductor of the said alternating current, and means for causing alternating current 115 derived from said source to traverse the winding on the armature of the relay device.

7. In a railway signaling system having one or more block-sections, the combination of one or more track-circuits for each block-section, each track-circuit comprising one or 5 more secondary batteries and a relay device adapted to respond in the movement of its armature to the presence or absence of current derived from said secondary batteries in its coils, a source of direct-current supply for 10 charging the said secondary batteries, wires or conductors for conveying the charging-current from the said source to the place or places where said current is to be used, means for connecting each of said secondary batteries alternately with the said conductors and with the track-rails of the block-section, a source of alternating-current supply and means for utilizing one of the conductors of the battery-charging system as one conductor 15 of the alternating current and means for using one or both track-rails of the railway as the other conductor of the said alternating current, of a transforming device for each track-section, having one terminal of its primary coil connected to one of the conductors of the battery-charging system and the other terminal connected to one of the track-rails of the railway, of means inserted in the circuit of the primary coil of the transformer 20 whereby the flow of direct current from the source of direct current to the track-rails of the railway is prevented, of means for connecting one terminal of the secondary coil of the said transforming device to one track-rail of the railway and of connecting the other terminal to the other track-rail of the railway, and means inserted in the circuit of the said secondary coil, whereby direct current from the track-rails of the railway is prevented 25 from flowing through the said secondary coil.

8. In a railway signaling system having one or more block-sections, the combination of one or more track-circuits for each block-section, each track-circuit comprising one or 45 more secondary batteries and a relay device adapted to respond in the movement of its armature to the presence or absence of current derived from said secondary batteries in its coils, a source of direct-current supply for 50 charging the said secondary batteries, wires or conductors for conveying the charging-current from the said source to the place or places where said current is to be used, means for connecting each of said secondary batteries alternately with the said conductors and with the track-rails of the block-section, a source of alternating-current supply and means for utilizing one of the conductors of the battery-charging system as one conductor 55 of the alternating current and means for using one or both track-rails of the railway as the other conductor of the said alternating current, of a transforming device for each

track-section, having one terminal of its primary coil connected to one of the conductors of the battery-charging system and the other terminal connected to one of the track-rails of the railway, of means inserted in the circuit of the primary coil of the transformer whereby the flow of direct current from the source of direct current to the track-rails of the railway is prevented, of means for connecting one terminal of the secondary coil of said transforming device to one track-rail of the railway and the other terminal of said secondary coil to one terminal of the relay device, the other terminal of said relay device being connected to the other track-rail of the railway. 65 70 75 80

9. In a railway signaling system having one or more block-sections, the combination of one or more track-circuits for each block-section, each track-circuit comprising a source of current-supply and a relay device 85 adapted to respond in the movement of its armature to the presence or absence of current in its coils derived from said source, of a source of alternating-current supply having one of its terminals connected to one of the track-rails of the railway and the other of its terminals connected to a wire or conductor laid or strung alongside and adjacent the railway, of a transforming device having one terminal of its primary coil connected to one track-rail of the railway and its other terminal connected to the said wire or conductor to which one terminal of the source of alternating current is in like manner connected, of a secondary coil forming part of said transforming device and means for causing the alternating current which is induced in the said secondary coil to traverse a winding of one or more convolutions and means for causing the said winding to encircle or embrace 90 95 100 105 the magnet-core of the relay device.

10. In a railway signaling system having one or more block-sections, the combination of one or more track-circuits for each block-section, each track-circuit comprising a source of current-supply and a relay device 110 adapted to respond in the movement of its armature to the presence or absence of current in its coils derived from said source, of a source of alternating-current supply having one of its terminals connected to one of the track-rails of the railway and the other of its terminals connected to a wire or conductor laid or strung alongside and adjacent the railway, of a transforming device having one terminal of its primary coil connected to one track-rail of the railway and its other terminal connected to the said wire or conductor to which one terminal of the source of alternating current is in like manner connected, of a secondary coil forming part of said transforming device and means for causing the alternating current which is induced in the 115 120 125

said secondary coil to traverse a winding of one or more convolutions and means for causing the said winding to encircle or embrace the armature of the relay device.

5 11. In a railway signaling system having a plurality of block-sections, the combination with a track-circuit comprising a relay for each block-section, of a means comprising a source of alternating current for each block-

section for dispelling the residual magnetism of the relay.

In testimony whereof I have signed my name to this specification in the presence of two subscribed witnesses.
